PULSATORT

Clifford J. Gleason, Leicester, Mass.

Application August 27, 1948, Serial No. 46,479

1 Claim. (Cl. 128-64)

1

This invention relates to squeezing and pulsating devices particularly adapted for use in the stimulation and reviving of muscular and nerve activity and in the restoration of normal circulation, particularly for use in neuritis, arthritis, bursitis, stiff hands, swollen limbs, and infantile shrunken limbs, with far more effective results than possible by hand massage or the like alone.

The principal object of the invention resides in the provision of specially shaped pulsators so designed as to be enabled to fit part of the body of the human being to be treated, as for example a limb thereof, these pulsators being provided with compressed air actuating means providing for pulsation and there preferably being two such pulsators which are adapted to be supplied with intermittent charges of air, in combination with membranous or thin rubber diaphragms or the like, which are in contact with the body part to be treated and which, therefore, exert pressure intermittently and preferably rhythmically thereto; the provision of a pair of pulsating applicators as above described which are selectively adaptable for use in simultaneous or alternate pulsations so that when applied to the body they may both exert pressure at the same time, in either side by side relation or applied to opposite sides of the same member; or they may be applied to pulsate alternately so as to press against one side of a member and then against the other side of the same member alternately.

Further objects of the invention reside in the provision of pulsator applicators as above described provided with rubber tubing long enough to reach the part of the body to be treated and having belts or webbing to apply the same thereto in any desired relation, in combination with the compressed air means above referred to to apply a squeezing effect stimulating and awakening nerve, muscular and circulatory functions in a unique manner, or selectively capable of being connected up to apply an alternating pulsating effect, for instance, in order to reach deep seated glands where a squeezing effect cannot be used and yet a deep pulsating effect may be given to cause the glands to disgorge fluids or to massage the same so as to enable the glands to function in the right way.

Other objects and advantages of the invention will appear hereinafter.

Reference is to be had to the accompanying drawings in which

Fig. 1 is a view in elevation of an applicator according to the present invention;

Fig. 2 is an edge view thereof;

2

Fig. 3 is an enlarged sectional view on line 3-3 of Fig. 1;

Fig. 4 is an enlarged sectional view on line 4-4 of Fig. 1;

Fig. 5 illustrates the two applicators as applied to a member of the human body arranged for squeezing effect; and

Fig. 6 is a view similar to Fig. 5 showing the device arranged for alternating pulsating effect.

Reference is hereby made to Patent No. 1,813,006, July 7, 1931, which illustrates a foot exercising device operated by compressed air. The present invention is a considerable improvement on the device as shown in the patent, as the present invention shows a construction which may be applied anywhere at all to the human body and which may have a simultaneous squeezing effect or an alternate pulsating effect, as will be later described.

20 As shown in Figs. 1, 2, and 3, the present invention includes primarily a pad-like pulsating applicator or pulsator generally indicated at 10 and it is to be understood that preferably there are two of these and they are used in pairs. Both 25 of them are similar, however, and only one, therefore, needs to be described. Each pad or pulsator is generally elongated and triangular and a little larger than the human hand spread out.

20 A relatively strong base member indicated at 12 is made of a material such as, for instance, leather, heavy rubber, plastic, and this forms the support for a pipe inlet 14 for a pipe or tube 16, more specifically shown in Fig. 4 and comprising a fitting 18 screw threaded into a washer 20 35 interiorly of the device and held thereto by the member 14. The pipe 16 is secured to the fitting 18 by a nut 2 or any other similar or desired device and a tube 24 may be simply slipped onto the pipe 16.

40 The same side of the base member 12, which supports the fitting 18, also supports some strong rigid loops 26 for the reception of webbing or belts 28 which may be provided with buckles or the like for adjustably securing the pulsating elements to the body part to be treated.

45 The opposite surface of the body member 12 is provided with a relatively heavy marginal rim 30 which is used to secure in place a membranous or rubber diaphragm 32 capable of extension to the 50 dotted line position clearly shown in Fig. 3 by means of compressed air being introduced into the pulsator through the pipe 16. The rim 30, diaphragm 32 and base member 12 are all secured together as by fasteners 34.

55 One form of use of the device is illustrated in

Figs. 5 and 6, wherein a pair of pulsator applicators are secured to opposite sides of an arm of the patient by means of the webs or belts 28 and the pipes 16 are secured by their tubes 24 to a fitting 36 receiving compressed air as, for instance, from a cylinder 38 so that the diaphragms of both applicators 10 are dilated at the same time to provide a deep seated squeezing effect on the member secured between the applicators.

However, if desired to impart an alternating pulsating effect, the tubes 24 are replaced by pipes 40 which are secured to opposite ends of an air cylinder 42, whereby one diaphragm is dilated while the other one is collapsed, thus providing for an alternating pulsating effect as applied to the body member of the patient.

This apparatus may be used not only for a mere massaging action but also to provide means compressing the arteries or the veins for a short space of time and releasing the same to encourage circulation and by repeated action this is believed to reestablish channels of circulation so that disorders resulting from poor circulation are greatly benefited.

By applying the device or both devices to the proper places, deep seated glands may be encouraged to operate normally and encourage the same to disgorge fluids that sometimes are not permitted to be discharged, for one reason or another, so as to insure that the glands function in a normal manner.

Having thus described my invention and the advantages thereof, I do not wish to be limited to the details herein disclosed otherwise than as set forth in the claim, but what I claim is:

A device for applying pulsations to the human anatomy, comprising a pair of similar applicators

each including a stiff elongated flat base tapering in width from one end to the other, a flexible diaphragm corresponding in shape to the base, means for securing the diaphragm to the base at their peripheries only, leaving the remainder of the diaphragm free to expand from the base under the application of fluid pressure, said securing means comprising a rigid marginal rim and fasteners for securing together the marginal rim, base and diaphragm, means for supplying fluid pressure to each diaphragm comprising a rigid tubular fitting extending through the base to but not through the expansible portion of the diaphragm, a tube extending from each fitting to a single source of pulsating pressure, and means for simultaneously securing the applicators to the human anatomy, comprising stiff web-receiving loops carried by the base adjacent opposite ends thereof and webs extending through corresponding loops for binding the applicators to the human anatomy.

CLIFFORD J. GLEASON.
